(57) **CLAIM**

The ornamental design for a rear cover for a utility vehicle, as shown and described.

DESCRIPTION

FIG. 1 is a perspective view of a rear cover for a utility vehicle showing our new design;

FIG. 2 is a left side view thereof;

FIG. 3 is a right side view thereof;

FIG. 4 is a front elevational view thereof;

FIG. 5 is a rear elevational view thereof;

FIG. 6 is a top plan view thereof; and,

FIG. 7 is a bottom plan view thereof.

The broken line showing of the utility vehicle in FIG. 1 and portions of the rear cover for a utility vehicle in FIGS. 1-7 is included for the purpose of illustrating environmental structure and forms no part of the claimed design.

1 Claim, 7 Drawing Sheets

FIG. 2

FIG. 3

FIG. 4

FIG. 5

FIG. 6
